UNITED STATES PATENT OFFICE.

HENRY FRANCIS KEIL, OF BRONXVILLE, NEW YORK.

LATCH.

SPECIFICATION forming part of Letters Patent No. 767,567, dated August 16, 1904.

Application filed December 9, 1903. Serial No. 184,499. (No model.)

To all whom it may concern:

Be it known that I, HENRY FRANCIS KEIL, a citizen of the United States of America, and a resident of Bronxville, in the county of West-
5 chester and State of New York, have invented a certain new and useful Latch, of which the following is a specification.

This invention relates to fastening devices and in particular to a catch by which either a 10 swinging or a sliding door, as a cupboard-door, may be securely held in the closed position and also readily opened when so desired; and it has for its object the provision of an 15 appliance of the kind set forth simple in construction, inexpensive to manufacture, and efficient in practical use.

To attain the desired end, this my invention consists in the construction, arrangement, and operation of parts herein set forth.

20 In order to enable my invention to be fully understood, I will proceed to explain the same by reference to the drawings which accompany and form a part of this specification, in which—

25 Figure 1 represents a side elevation of my catch and support therefor, partly in section. Figs. 2 and 3 are vertical sections of my fastener in latched and unlatched position, respectively. Figs 4 and 5 are views in detail 30 of the various parts of my catch, and Fig. 6 is a view of another casing or shell constructed according to my invention.

Like letters of reference indicate like parts in all the views.

35 Referring particularly to the drawings, A denotes the plunger used in my catch, consisting ordinarily of a shell a , a washer a' , and a cover a'' . The shell a and washer a' are each slotted, the said slots being constructed and 40 arranged to register with the slots formed on the opposite sides of the enlargement d of the plate D , and after being mounted upon the said plate the cover a'' is applied to the same and the annular flange of the said cover forced 45 inwardly over the flaring mouth of the shell a , thus rigidly fastening the parts together.

The casing or shell B of my catch is preferably struck up from a sheet of metal and consists of a flaring base portion b^2 , a cylindrical 50 neck b , and an annular hollow head b' , the same

providing a chamber in connection with a transverse diaphragm or disk C , formed with a longitudinal guide or rectangular sleeve C' , having an orifice C^2 , and which disk is constructed and arranged to register in contour 55 with and to loosely fit the interior of the flaring portion of the base b^2 .

The lever D' is made with a socket d' at one end in order to loosely contain the rounded extremity d^3 of the plate D and to form an 60 elbow-joint and is formed with a hook d^2 at the end of the same, constructed and arranged to engage a striker or keeper E .

In order to assemble the parts, the plunger A and the plate D , fastened thereto, are first 65 inserted in the apertured head b' of the shell B . The spring F is then slipped over the said plate D , after which the lever D' is engaged with the plate D , and, lastly, the diaphragm or disk C is inserted in the flaring base of the 70 casing B , and the flap of the latter is forced inwardly over the edge of the disk C to rigidly secure the same to the casing B , thus holding all the parts in proper position. The lever D' is fulcrumed by passing the pin G through 75 the orifice C^2 of the disk C and the orifice d^4 of the lever D' .

In lieu of striking up the shell B from one sheet of metal manifestly the same may be constructed of a body portion B' , an intermediate washer B^3 , and a head B^2 , the annular flange of which may be forced inwardly over the horizontal edge formed at the top of the part B' , as shown in Fig. 6.

In operation my catch is ordinarily applied 85 to a door or other movable articles and the keeper or striker therefor is fastened to the jamb or other support. When the door, &c., is caused to assume a closed relation, the lock-lever D' will engage the striker E and the 90 hook d^2 will be raised or forced in a backward direction around its pivot G until it rides over the edge of the striker, whereupon the spring F , lying between the disk C , which forms a bearing for the said lever, and the shell a of the plunger A , will cause the lock-lever D' to assume a practically horizontal position once more, thereby securely holding the door, &c., in a closed relation. In order to open the door, &c., again, the plunger A is pushed in- 95 100

wardly, thereby causing the lock-lever D to rise or be moved in a rearward position again a sufficient distance for the hook d^2 to clear the edge of the keeper or striker E.

5 As it is evident that many changes in the construction, form, proportion, and relative arrangement of parts might be resorted to without departing from the spirit and scope of my invention, I would have it understood 10 that I do not restrict myself to the particular construction and arrangement of parts shown and described, but that such changes and equivalents may be substituted therefor, and that

15 What I claim as my invention is—

1. As a new article of manufacture a latch comprising a plunger, consisting of a hollow head and a flat body portion constructed of sheet metal, a lock-lever, an elbow-joint there- 20 between, and a casing for the same made of sheet metal and consisting of a hollow shell and a transverse disk formed with a longitudinal guide and a bearing for said plunger and lock-lever.

25 2. As a new article of manufacture a latch

comprising a plunger consisting of a hollow head and a flat body portion constructed of sheet metal, a lock-lever, and a casing for the same made of sheet metal and consisting of a hollow shell and a transverse disk formed with 30 a bearing for the said lock-lever.

3. As a new article of manufacture, a latch comprising a plunger constructed of sheet metal and consisting of a flat body portion and a hollow head formed by a shell, a washer 35 to which the end of the body portion is riveted, and a cap or cover to hold the whole together, a lock-lever, and a casing for the same formed of sheet metal and consisting of a hollow shell and a transverse disk constructed 40 with a bearing for the said lock-lever.

In testimony of the foregoing specification I do hereby sign the same, in the State of New York, in the city and county of New York, this 23d day of November, 1903.

HENRY FRANCIS KEIL.
